(57) **CLAIM**

An ornamental design for a foldable firearm, as shown and described.

DESCRIPTION

FIG. 1 is a top/rear/left perspective view of the firearm, open.
FIG. 2 is a left plan view of the firearm, open.

FIG. 3 is a right plan view of the firearm, open.

FIG. 4 is a top plan view of the firearm, open.

FIG. 5 is a bottom plan view of the firearm, open.

FIG. 6 is a front plan view of the firearm, open.

FIG. 7 is a rear plan view of the firearm, open.

FIG. 8 is a top/front/left perspective view of the firearm, open.

FIG. 9 is a bottom/front/left perspective view of the firearm, open.

FIG. 10 is a bottom/front/right perspective view of the firearm, open.

FIG. 11 is a top/front/right perspective view of the firearm, open.

FIG. 12 is a bottom/rear/left perspective view of the firearm, open.

FIG. 13 is a top/rear/right perspective view of the firearm, open.

FIG. 14 is a bottom/rear/right perspective view of the firearm, open.

FIG. 15 is a top/rear/left perspective view of the firearm, closed.

FIG. 16 is a left plan view of the firearm, closed.

FIG. 17 is a right plan view of the firearm, closed.

FIG. 18 is a top plan view of the firearm, closed.

FIG. 19 is a bottom plan view of the firearm, closed.

FIG. 20 is a front plan view of the firearm, closed.

FIG. 21 is a rear plan view of the firearm, closed.

FIG. 22 is a top/front/left perspective view of the firearm, closed.

FIG. 23 is a bottom/front/left perspective view of the firearm, closed.

FIG. 24 is a bottom/front/right perspective view of the firearm, closed.

FIG. 25 is a top/front/right perspective view of the firearm, closed.

FIG. 26 is a bottom/rear/left perspective view of the firearm, closed.

FIG. 27 is a top/rear/right perspective view of the firearm, closed; and,

FIG. 28 is a bottom/rear/right perspective view of the firearm, closed.

The broken line showing of FIGS. 3, 5, 6, 9, 10, 12 and 14 is included for the purpose of illustrating portions of the Foldable Firearm that forms no part of the claimed design.
